UNITED STATES PATENT OFFICE.

RAYMOND A. HEISING, OF EAST ORANGE, NEW JERSEY, ASSIGNOR TO WESTERN ELECTRIC COMPANY, INCORPORATED, OF NEW YORK, N. Y., A CORPORATION OF NEW YORK.

HIGH-FREQUENCY CARRIER SIGNALING.

Application filed March 26, 1920. Serial No. 368,881.

To all whom it may concern:

Be it known that I, RAYMOND A. HEISING, a citizen of the United States, residing at East Orange, in the county of Essex, State of

5 New Jersey, have invented certain new and useful Improvements in High-Frequency Carrier Signaling, of which the following is a full, clear, concise, and exact description.

10 This invention relates to multiplex signaling in which a plurality of messages may be transmitted simultaneously over a signaling circuit and is an improvement over the system described and claimed in applicant's Patent No. 1,313,483 granted August 19, 1919.

By means of a system of the type disclosed in the above-mentioned patent, it is possible to transmit several messages simultaneously from one station by means of voice modulated carrier waves of high frequency and at the same time to receive simultaneously several messages, transmitted from another station in the same manner, i. e., by 25 means of voice modulated carrier waves of high frequency. The present invention relates to a particular relationship between the frequencies of the outgoing and the incoming waves, i. e., between the waves sent over 30 the line by one station and the waves sent over the line in the opposite direction by the distant station.

In the type of multiplex telephone system disclosed in the patent, a plurality of messages can be simultaneously sent over the line by means of the expedient in which each one of a plurality of transmitters sends out a modulated wave having a characteristic frequency, which frequency is different from that of the other transmitters. The receiving devices at the distant end of the line are tuned to the respective frequencies of the corresponding transmitting circuits. A plurality of messages can be transmitted over 45 the line in the opposite direction in the same manner, and the transmission and reception of signals in opposite directions can be carried on simultaneously. In an early system of this general type, the frequencies transmitted in the two directions were the same, so that the frequency range occupied by the system as a whole was the same as the frequency range occupied by the frequencies at which either of the stations was working.

By means of this arrangement, a maximum 55 economy of frequency range can be obtained, as is readily apparent. This arrangement, however, has been found to be inefficient and incapable of commercial use on account of interference between transmitting and receiving circuits at the same station and between receiving circuits at either station. In order to avoid interference effects, the frequency ranges for the frequencies transmitted in the two directions were then made 60 to occupy adjacent but separate frequency ranges. By means of this arrangement, there was a minimum interference effect, but the frequency range of the system, by means of which the same number of messages could 65 be transmitted simultaneously as before, was substantially doubled.

In the system of this invention, it is proposed to relate the two groups of frequencies in such a manner that the frequencies of 75 waves transmitted from one station are intermediate those transmitted by the distant station. It has been discovered that by means of this "staggered" arrangement of frequencies the same desired result may be 80 obtained as in the above-mentioned earlier arrangement as regards the total frequency interval used, but with no sacrifice of clarity of tone or freedom from interference. In other words, by means of this invention, it 85 is possible to compress the number of frequencies transmitted in both directions within the smallest interval consistent with efficient transmission and reception of speech signals and this is accordingly stated as one 90 of the objects of the invention. The desirability of using as small a frequency range as possible in carrier current signaling is shown, for example, by the fact that radiation losses are greater with the higher frequencies.

It may be stated as a further object of the invention to make possible within a given range of frequencies, the use of a maximum number of transmission frequencies.

A still further object of this invention is to enable the use of a relationship of frequencies transmitted over the line in opposite directions, by means of which, with a given frequency range and with a given number of frequencies, a minimum degree of interference results.

Proceeding to a detailed description of the invention, reference is made to the drawing, in which the figure shows diagrammatically the circuit connections for a plurality of transmitter and receiver circuits.

Signals may be sent over the line L to a distant station or stations from any one or all of the transmitter circuits T_1 , T_2 , T_3 . And the line L is adapted to transmit signals from a distant station or stations to any one or all of the receiver circuits, R_1 , R_2 , R_3 , or to any one or all of the alternative receiver circuits, R'_1 , R'_2 , R'_3 .

The transmitter circuits T_1 , T_2 , and T_3 , are substantial duplicates, the only difference being in the adjustments of the various elements so that each transmitter circuit may transmit oscillations of a frequency different from that of all the others, both at the end of the line shown and at the other end of the line. The same is true of the receiver circuits R_1 , R_2 , R_3 , R'_1 , R'_2 , R'_3 , each of which is tuned to the frequency of its corresponding transmitter at the other end of the line.

In each transmitter circuit, the high frequency oscillations produced by the oscillator O which may be characterized as carrier oscillations are modulated in accordance with signal waves by means of the transmitter t and the modulator l. The oscillator herein described is the invention of another and constitutes a part of the present invention only as one element of the system. The modulator per se is likewise the invention of another and constitutes a preferred form of means for causing the amplitude of the feeble high frequency oscillations to vary in accordance with the wave form of the message wave. This is accomplished by impressing the message wave or impulse together with the high frequency oscillations on the input circuit of a thermionic device herein styled a modulator. The modulated oscillations are amplified by the power tubes or amplifiers 2 and 3 and are impressed on the line through the transformer 4.

The oscillator O comprises a variable transformer 8 supplied with energy from battery 9, variations in the battery current through the primary 10 causing corresponding variations in the E. M. F. induced in the secondary 11. The frequency of the oscillations is determined by the value of the adjustable condenser 12, shunted across the adjustable primary 10 and which forms with the latter a tuned circuit. Variations in the battery current are produced by the vacuum tube 13 which comprises a cathode or filament 14 heated by current supplied from battery 15 through the adjustable resistance 16. Terminal 17 of the filament 14 makes an adjustable connection 18 with the transformer primary 10. The positive terminal 19 of battery 9 is connected to the anode or

plate 20, the negative terminal 21 being connected by lead 22 to one terminal of condenser 12 and one terminal of transformer primary 10, the condenser being in shunt to the primary, the other terminals of the primary and the condenser are connected by lead 23 to the grid 24.

As to the operation of the oscillator, the battery 9 supplies current through a circuit including plate 20, filament 14, lead 17, through that part of the primary 10 included by the adjustable connection 18 to the negative terminal of the battery. This comprises what may be termed the secondary circuit of the oscillator, the primary circuit of which includes filament 14, lead 17, that portion of transformer primary 10 between adjustable connector 18 and lead 23, and the grid 24. Variations in the potential between filament 14 and grid 24 cause amplified variations in the current delivered by the battery in the secondary circuit. Furthermore, the battery current in the secondary circuit including electrode 20 and filament 14 is a function of the potential of grid 24. The two parts of the transformer primary 10 are inductively related and variations in the battery current through that part of the transformer primary 10 included in the secondary circuit of the oscillator induce an E. M. F. in the remaining part of the transformer primary 10 included in the primary circuit of the oscillator.

The current in the oscillator secondary circuit is established by the battery 9, such increase in the current being alternately opposed and aided by the consequent potential of the grid 24, caused by the inductive action of the two parts of the transformer primary 10. This is productive of oscillations in the battery current through the transformer primary 10 and the period of such oscillations is determined by the adjustment of the regulable condenser 12, shunted across the transformer primary 10.

Variations in the current in transformer primary 10 cause corresponding variations in the E. M. F. induced in the transformer secondary 11 in the transmitter circuit. The oscillations set up by the transformer secondary 11 are combined in line 25 with the oscillations produced by the transmitter t which causes variations in current supplied by battery b to transformer primary 26. The line 25 makes an adjustable connection with resistance 28 shunted across transformer secondary 27 to vary the amplitude of the transmitter oscillations impressed on the modulator grid 29.

The primary circuit of the vacuum tube or modulator includes grid 29, secondary winding 11, winding 27 and resistance 28 in shunt to the latter, battery 30 and filament or cathode 31 heated by battery 32. The battery 30 impresses a negative potential on

the grid or auxiliary electrode 29 by having its negative terminal connected thereto. The secondary circuit of modulator 7 comprises filament 31 connected to negative of battery 32, the positive terminal of which is connected to the tuned circuit including inductance 33 and capacity 34 in parallel, thence to electrode or plate 35.

The circuit including inductance 33 and capacity 34 is tuned to the oscillator frequency and offers high impedance thereto acting as an anti-resonant circuit, so that these high frequency oscillations will be sent through condensers 36 and 37 and resistance 43. The tuned circuit 33, 34, however, offers low impedance to the passage of currents of any frequencies other than those of the oscillator frequency.

The drop in potential of the modulated high frequency oscillations across resistance 43 is impressed on the primary circuits of the vacuum tubes, power tubes or amplifiers 2 and 3. The vacuum tube 2 encloses cathode or filament 40, anode or plate 46, and the auxiliary electrode or grid 38. Similarly the vacuum tube 3 encloses filament or cathode 41, grid 39, and anode or plate 47. Condenser 36 is connected to grids 38 and 39, and condenser 37 is connected to filament 40 and 41. The battery 42 has its negative terminal connected through resistance 43 to grids 38 and 39 while its positive terminal is connected to filaments 40 and 41. The latter filaments are heated by current from battery 44, the current being regulated by the adjustable resistance 45.

The secondary circuits of the amplifiers 2 and 3 include electrodes 46 and 47 in parallel, primary 48 of transformer 4, and battery 49, the negative terminal of which is connected to the filaments 40 and 41.

The secondary winding 51 of transformer 4 serves as a source of amplified modulated high frequency oscillations, which are to be impressed on the line L for transmission to a properly tuned receiving apparatus at the other end of the line L. In similar way, modulated oscillations may be impressed on the line L by means of transformers 5 and 6 in the transmitter circuits T₂ and T₃, respectively.

The elements of the transmitter circuits T₂ and T₃ are identical with those of transmitter circuit T₁, the only difference being in the adjustment of the various circuits whereby each transmitter circuit impresses on the line L a carrier frequency different from that impressed by the other transmitter circuits.

It would be unsatisfactory to have the secondary windings of transformers 4, 5 and 6 directly connected in the line L because each secondary winding would serve as a choke coil for current transmitted from all of the others, and each secondary winding

would thereby impede the passage of the high frequency currents.

To effectively remove the impedance that secondary winding 51 would otherwise offer to currents from transmitter circuits other than T₁, the anti-resonant circuit C₁ is connected in shunt to the winding 51. This anti-resonant circuit comprises condenser 55 and inductance 54 which are supplied in parallel by the winding 51.

The anti-resonant circuit C₁ is tuned to the high frequency supplied by transmitter circuit T₁. The anti-resonant circuit C₁ then offers a path of high impedance to currents supplied by transmitter circuit T₁ and these currents flow to the line L through the comparatively low resistance path provided by the elements 51 and 50. This low resistance path is tuned to the frequency supplied by transmitter circuit T₁ by means of adjustable condenser 50.

The currents supplied by transmitter circuits T₂, T₃ or by the transmitter circuits at the other end of the line, being of a frequency different from that for which anti-resonant circuit C₁ is tuned, find this anti-resonant circuit a path of low impedance.

It is to be noted then that an anti-resonant circuit, comprising an inductance and a capacity supplied from a source in parallel, when tuned to the frequency of the source, provides a high impedance path to currents from that source and a low impedance path to currents of other frequencies. The usual type of oscillation circuit includes an inductance and a capacity connected in series with a source and tuned to the frequency of that source in order that this circuit may be more receptive to currents from that source than to currents of frequencies different from that for which said circuit is tuned.

The term "anti-resonant" circuit is accordingly here used to designate a circuit which offers high impedance to the passage of currents of the frequency to which it is tuned, but which provides a low impedance path for currents of other frequencies.

In a manner similar to that described in connection with transmitter circuit T₁, the transmitter circuits T₂ and T₃ are provided with adjustable condensers 52 and 53 and with anti-resonant circuits C₂ and C₃, respectively. Inductance 56 and capacity 57 are provided in anti-resonant circuit C₂ and anti-resonant circuit C₃ includes inductance 58 and condenser 59. Anti-resonant circuits C₂ and C₃ are tuned to the frequencies supplied by transmitted circuits T₂ and T₃, respectively.

Each of the transmitter circuits T₁, T₂, T₃, supplies carrier oscillations of a frequency different from those supplied by the remaining transmitter circuits. Hence, each anti-resonant circuit provides a path of high impedance for currents from its associated

transmitter circuit and a path of low impedance for currents from the other transmitter circuits.

The block R at the other end of the line 5, L, conventionally represents a plurality of receiver circuits, each of which is tuned to the frequency of one of the transmitter circuits T_1 , T_2 , T_3 .

Connected in the line L is the transformer 10 primary 60, adjustable with respect to the secondary 61 which supplies the energy of the incoming signals to the receiver circuits R_1 , R_2 , R_3 , R'_1 , R'_2 , R'_3 .

To provide a balancing network for this 15 system, transmitter lead 62 is connected to the line L while lead 63 is connected to the middle point 64 of primary 60. Between the primary 60 and the point of connection of lead 62 with line L there is connected 20 an artificial line 65 which, for the reasons fully disclosed in the above mentioned patent should preferably be non-reactive, i. e. consist of a substantially pure resistance. Viewing the connections in a different way, 25 the artificial line 65 and that part of primary winding 60 connected between it and the connection 64, comprises a bridge connection, or shunt about the transmitter circuits connected to leads 62 and 63.

If the impedance of artificial line 65 is 30 exactly the same as the impedance of the line L, then currents due to transmitter circuits T_1 , T_2 , T_3 , in the two halves of primary winding 60 will be equal in value, and 35 as these currents flow in opposite directions in the two halves of the primary winding 60, the resultant effect on the secondary 61 is nil, so that the outgoing energy has no effect on the local receiving apparatus. However, 40 current of the incoming signals passes in the same direction through the two parts of primary 60, so that the incoming energy is transferred to the local receiving apparatus. The local transmitting path 62, 54, 56, 58, 45 63 and the local receiving path 74, 76, 75, are therefore conjugate at the carrier frequencies.

The transformer secondary 61 is connected either to the receiver circuits R_1 , R_2 , R_3 , 50 or to receiver circuits R'_1 , R'_2 , R'_3 . If it is desired to separate the different frequencies before amplifying and detecting, the transformer secondary 61 is connected to receiver circuits R'_1 , R'_2 , R'_3 , connection being 55 made by lines 66 and 67 to primary windings of the adjustable transformers 68, 69 and 70. By means of the variable condensers 71, 72 and 73 the secondary circuits of the transformers 68, 69 and 70 are each tuned to the 60 carrier frequency supplied by the corresponding transmitter circuit at the other end of the line L. The transmitter and receiver circuits at the other end of the line are similar to those shown in detail and are conven-

tional represented by the blocks T and R. 65 To each tuned circuit R'_1 , R'_2 , R'_3 is connected the amplifying, detecting and receiving apparatus.

Preferably, however, the transformer secondary 61 is connected to receiving circuits 70 R_1 , R_2 , R_3 , through the circuit 74-75 which includes a common device for amplifying the energy incoming over the different channels.

As shown, transformer secondary 61 is 75 connected by lines 74 and 75 to the primary or input circuit of the amplifier 76 which comprises the evacuated vessel 77, enclosing cathode or filament 78 heated by battery 79, the grid or auxiliary electrode 80 and the 80 plate or anode 81. Line 74 is connected to the grid 80 and line 75 to the filament 78. The secondary or output circuit of the amplifier 76 comprises anode 81, the primary windings of the variable transformers 83, 84, 85, 85, in series, and the battery 82, the negative terminal of which is connected to the cathode 78. It will be noted that since the amplifier 76 does not have an exactly linear characteristic, it tends to act as a modulating 90 device and if the transmitted as well as the received high frequency currents were allowed to act thereupon, it would tend to cause intermodulation between the transmitted and received currents. 95

Amplified modulated oscillations of a given frequency are selected by the tuned circuit comprising the secondary winding of transformer 83 and the variable condenser 86, shunted thereacross, and these 100 oscillations are impressed on the input circuit of the detector 87. This detector comprises an evacuated vessel 88 which encloses cathode 89 heated by battery 90, grid 91 and plate 92, the grid 91 and filament 105 89 forming the terminals of the primary or input circuit connected to the secondary winding of transformer 83. The anode 92 and cathode 89 are the terminals of the detector output circuit and which includes 110 the battery 93, having its negative terminal connected to the cathode 89, and the primary winding of transformer 94, the secondary 115 of which is connected to the receiver 95.

The receiving circuits R_2 and R_3 are substantial duplicates of receiving circuit R_1 , the only difference being in the adjustments of the condensers and inductances, whereby each is tuned to a frequency different from that of the others, this frequency being that of the oscillations furnished by the generator in the corresponding transmitter circuit at the other end of the line. 120

It will be apparent, therefore, that in the preferred form, the incoming waves are 125 amplified in a single device and then transmitted to the various receiving circuits where they are selected and detected to

yield the signal currents which are supplied to the respective signal indicating instruments or receivers.

The above description of the structure and arrangements of circuits is the same as that disclosed in the patent referred to above. It is the essence of this invention, however, that the transmitting frequencies of circuits T_1 , T_2 , and T_3 shall have a certain definite relation to the frequencies of the station T . For example, if it be assumed that the carrier frequencies of circuits T_1 , T_2 , T_3 , are respectively 5,000, 10,000 and 15,000 cycles, the corresponding frequencies of currents at station T may be 7,500, 12,500 and 17,500. It necessarily follows that the frequencies to which receiving circuits R_1 , R_2 , R_3 are tuned are respectively 7,500, 12,500 and 17,500. That this "staggering" of frequencies can be accomplished without unduly increasing interference can be shown by the following explanation of the phenomenon:

The efficiency of a system such as that disclosed is largely measured and determined by the presence or absence of interference. There may be interferences between the receiving circuits at a station, whereby an incoming signal from the distant station may influence a receiver other than the one tuned to the particular carrier frequency. This results in the phenomenon of cross-talk. Or signals transmitted over the line by any one of the transmitters T_1 , T_2 , T_3 may influence receiving circuits R_1 , R_2 , R_3 , this phenomenon being known as side tone. Cross-talk can be eliminated by sharply tuning the receiving circuits, the minimum frequency interval between adjacent receiving circuits, and hence between transmitting circuits, being dependent upon the degree of selectivity secured by the particular tuned circuits used, and on the maximum allowable interference. Interference between the transmitting circuits is slight as compared with interference between receiving circuits. Side tone can be largely eliminated by the balancing net-work including the artificial line 65, as has been pointed out.

The balancing net-work therefore can be made much more effective than the tuned circuits for the purpose of eliminating side tone interference, and hence a smaller frequency difference between circuits T_1 and R_1 , for example, than between T_1 and T_2 or R_1 and R_2 , is allowable. If the frequencies transmitted in the two directions for each channel were the same and the frequency interval between T_1 , T_2 and T_3 and R_1 , R_2 and R_3 was the minimum permissible to reduce cross-talk to a satisfactory value, the balancing net-work would not be effective for eliminating side tone. However, if the group of frequencies trans-

mitted from one station, that is, R_1 , R_2 , R_3 or T_1 , T_2 , T_3 were displaced so that the frequency interval between them and that between the frequencies of the other group is maintained a minimum to eliminate interference due to cross-talk while the frequency interval between the successive frequencies used in this system is made approximately one-half that between the frequencies within each group, a system which would operate satisfactorily would be provided. In such a system, the frequencies of the waves transmitted in opposite directions will alternate with one another, while without changing the frequency interval for reducing cross-talk to a satisfactory value, a frequency spacing that will enable the balancing network to eliminate side tone is provided.

Using the same frequency interval as before between receiving circuits, the frequency transmitted from one station will be 5, 10 and 15 thousand, and the frequencies transmitted from the other stations will be 7,500, 12,500 and 17,500. In order not to exceed the permissible cross-talk interference, it has been found that with the "staggered" arrangement described above, it is necessary to increase somewhat the frequency interval between receiving circuits. However, in spite of this increase there results a large net gain over the arrangement heretofore used in practice, which involved completely separating the two frequency groups. Although perhaps as great a frequency interval as has been indicated above between frequencies of circuits T_1 and R_1 etc., is not necessary in order that interference between these circuits shall not exceed the practical limit which determined the spacing of T_1 , T_2 etc., it is pointed out that the overall frequency range is not substantially increased by causing the frequency interval between T_1 and R_1 , for example, to be as great as half the frequency interval between T_1 and T_2 or R_1 and R_2 instead of the smallest permissible frequency interval which would reduce side-tone to such a value that its interference would be negligible, and that with this spacing there will result a minimum amount of side tone interference. Accordingly, the arrangement described is to be preferred, although the invention is not necessarily so limited. Nor are the frequency values given to be considered as more than illustrative. In fact it is not necessary, or even desirable, that the interval between successive transmitting frequencies including frequencies in both directions be the same throughout the frequency range. The most efficient spacing is that in which the frequency interval is larger as the frequency becomes greater. For example, the following frequencies may

be used in telephone transmission 20, 26, 32, 38, 44, 50, 56, 62, 70, 78, 86, and 95 thousand cycles. In general it would be desirable to have the increase in frequency differences more uniform.

For carrier current telegraphy the following values have been used in one direction: 3350, 3850, 4350, 4880, 5450; 6090, 6790, 7580, 8470, 9460; and the following 10 frequencies in the other direction; 3600, 4100, 4610, 5160, 5760, 6420, 7170, 8010, 8950, 10,000. The respective frequency differences are then, 250, 250, 250, 250, 260, 270, 280, 290, 310, 330, 340, 360, 380, 410, 15 430, 460, 480, 510, 540. It is seen that these intervals increase progressively as the carrier frequencies forming the boundary frequency for these intervals, respectively, increase considering either the lower or the 20 higher of the two boundary frequencies as the reference frequency throughout the range. Although the frequency intervals vary from 250 to 540 in the case stated; it is sometimes desirable to make 25 them vary from as low a frequency as 100 cycles and to a higher frequency than that given. As has been pointed out previously this frequency interval is determined by the degree of selectivity secured 30 by the tuned circuits and by the balanced circuits, more particularly by the former. Experimental tests have furnished data from which curves have been plotted, for different degrees of selectivity between 35 frequencies transmitted and corresponding intervals. These curves, if extended, would pass through the origin and the coordinates progressively increase or decrease together but the curves are not linear, as is indicated 40 for example by the values given above in which the ratio of frequency difference to boundary frequency decreases as the boundary frequency increases.

Although the numerical example given 45 above has reference to telegraphy, the underlying theory and reasoning apply equally well to any system using a plurality of carrier frequencies and accordingly would apply to telephony.

50 It should be explained that it is not necessary for a conversation to be carried on over circuits which have adjacent frequencies, nor is it necessary that the two frequencies required for conversation have the 55 same relation with each other for each pair of circuits comprising a conversational unit. There are in fact practical reasons urging the use of frequencies as widely different as possible. For example it might well happen 60 that at a particular time the system might be used for a single conversation. Obviously for this condition there will be the least interference when there is a maximum separation of the two frequencies corresponding to a conversation. Such an ar-

angement is not inconsistent with the use 70 of the system to transmit the maximum number of impulses simultaneously. There is an additional advantage in the arrangement suggested over the simpler arrangement in which the adjacent frequencies are used, in that if all the circuits are simultaneously being used to transmit a plurality 75 of conversations with the latter arrangement, and if, for any reason, the balancing network or the tuning becomes ineffective for producing sufficient selectivity for normal use, conversation would be made impossible over each of the circuits; whereas with the former arrangement a conversation may 80 still be carried on over any one pair of circuits and perhaps over more than one pair of circuits sufficiently separated from each other, depending on the degree of selectivity 85 remaining.

It is to be understood that the values of 90 frequencies given throughout this specification are the values of the carrier frequencies. The frequency of the voice modulated wave in a carrier telephone system 95 would vary above and below this frequency within the limits determined by the voice frequencies, the range occupied by the frequencies corresponding to a carrier frequency constituting a band of frequencies. 100

Although the drawing discloses the use 100 of selective tuning means at transmitting and receiving circuits for preventing intermodulation between transmitting currents and cross-talk interference between the receiving circuits, it is pointed out that the use of band filters would generally be as effective for this purpose as the means shown, and would have certain advantages 105 thereover in particular systems involving the invention, as for example in carrier telephony, because of the comparative freedom of band filters from distorting properties over a considerable range of frequencies. 110 In this connection reference is made to British Patent 131,426 for a disclosure of the use of band filters in a relation similar to that suggested.

In telephone systems it is the interference 115 between bands rather than between the carrier frequencies that must be taken into account. This in no wise changes the principles above discussed, upon which this invention is based, and throughout the specification and claims where the carrier frequency is mentioned it is to be understood 120 that bands of side frequencies may or may not be present. In general the spacing mentioned is that designed more specifically for telephony but, as is well understood, side bands may be present in telegraph or other transmission systems and these would in general be comparable with the magnitude of those in telephone systems, although 125 probably somewhat narrower. 130

The advantages of the invention here stated as applied to a carrier telephone system apply also to other carrier current signaling or other carrier current transmission systems.

The invention in its broadest aspect is obviously not restricted to a "wire" system, and that the line L may be inductively or conductively disposed with reference to receiving or transmitting apparatus.

What is claimed is:

1. A multiplex transmission system comprising a combined transmitting and receiving station, a plurality of selective transmitting circuits at said station, and a plurality of selective receiving circuits at said station, one of said transmitting circuits and one of said receiving circuits being used to constitute the terminal apparatus for each two-way unit of the system, the said transmitting circuits being adjusted to transmit currents of frequencies which are different from and alternating with the frequencies to which said receiving circuits are adjusted.

2. A multiplex transmitting system comprising a combined transmitting and receiving station, a plurality of selective transmitting circuits at said station, means for impressing upon each of said transmitting circuits a high frequency current, a plurality of receiving circuits at said station, each selective to the frequency of a received current and means associated with each of said receiving circuits for obtaining a low frequency current from said received high frequency current, the said transmitting circuits being adjusted to transmit currents of frequencies which are different from and alternating with the frequencies to which said receiving circuits are adjusted.

3. A multiplex high frequency signaling system comprising a combined transmitting and receiving station, a plurality of selective transmitting circuits at said station, and a plurality of selective receiving circuits at said station, one of said transmitting circuits and one of said receiving circuits being used to constitute the terminal apparatus for each two-way unit of the system, the said transmitting circuits being adjusted to transmit currents of frequencies which are different from and alternating with the frequencies to which the said receiving circuits are adjusted.

4. A multiplex telephone system comprising a combined transmitting and receiving station, a plurality of selective transmitting circuits at said station, means for impressing upon each of the said transmitting circuits a voice modulated high frequency carrier current, a plurality of selective receiving circuits at said station, and means associated with each of said receiving circuits for obtaining a voice current

from the received high frequency current, the said transmitting circuits being adjusted to transmit currents of frequencies which are different from and alternating with the frequencies to which said receiving circuits are adjusted.

5. A multiplex transmitting system comprising a combined transmitting and receiving station, a plurality of selective transmitting circuits at said station, means for impressing upon each of the said transmitting circuits a high frequency current, a plurality of selective receiving circuits at said station having a common amplifying means associated therewith on the input side, and means associated with each of said receiving circuits for obtaining a low frequency current from the received high frequency current, the said transmitting circuits being adjusted to transmit currents of frequencies which are different from and alternating with the frequencies to which said receiving circuits are adjusted.

6. A high frequency line, an incoming line and an outgoing line conjugately connected to said high frequency line, a plurality of transmitting circuits adapted for multiplex carrier current transmission associated with said outgoing line, and a plurality of receiving circuits similarly adapted for multiplex carrier current reception associated with said incoming line, the said transmitting circuits being adjusted to transmit currents of frequencies which are different from and alternating with the frequencies to which said receiving circuits are adjusted.

7. A transmission line, an incoming and an outgoing circuit, means interconnecting said line and said circuits whereby said circuits are conjugate for all frequencies transmitted over said line, a plurality of modulated carrier current transmitting and detecting circuits associated respectively with said incoming and outgoing circuits and each selective of a different carrier frequency, the carrier frequencies of the said transmitting circuits being different from and alternating with the carrier frequencies to which said detecting circuits are adjusted.

8. A multiplex transmitting system comprising a combined transmitting and receiving station, a plurality of selective transmitting circuits at said station, means for impressing upon each of said transmitting circuits a high frequency current, a plurality of selective receiving circuits at said station and means associated with each of said receiving circuits for obtaining a low frequency current from the received high frequency current, the said transmitting circuits being adjusted to transmit currents of frequencies which are intermediate the frequencies to which said receiving circuits are adjusted, the frequency of the current in

each transmitting and receiving circuit differing by a constant percentage from the next lower frequency for the two directions considered as a whole.

5. 9. A multiplex transmitting system comprising a combined transmitting and receiving station, a plurality of selective transmitting circuits at said station, means for impressing upon each of said transmitting circuits a high frequency current, a plurality of selective receiving circuits at said station and means associated with each of said receiving circuits for obtaining a low frequency current from the received high frequency current, the said transmitting circuits being adjusted to transmit currents of frequencies which are different from and alternating with the frequencies to which said receiving circuits are adjusted, the frequency interval between the adjacent frequencies including those used for transmitting in both directions being different for different parts of the frequency scale and increasing progressively as the frequency increases.

10. A system as defined in claim 2, in which the transmitting and receiving circuits are adjusted to frequencies such that the intervals between adjacent carrier frequencies increase progressively over the range of carrier frequencies.

11. A multiplex transmission system comprising two intercommunicating stations, a plurality of means at each of said stations for transmitting to the other station a plurality of alternating currents, the frequencies of the currents transmitted by one station being different from those transmitted by the other station and alternating therewith.

12. A multiplex carrier current telephone system comprising two intercommunicating stations, a plurality of means at each of said stations for transmitting to the other station a plurality of voice modulated carrier currents, the carrier frequencies of the currents transmitted by one station being different from those transmitted by the other station and alternating therewith.

13. A multiplex signaling system comprising in combination a plurality of communicating selective transmitting and receiving circuits, the said transmitting circuits being adjusted to transmit currents of frequencies which are different from and alternating with the frequencies to which said receiving circuits are adjusted.

14. A multiplex signaling system comprising in combination a high frequency line, a plurality of transmitting circuits operatively associated with said line, and a plurality of receiving circuits operatively associated with said line and adapted to communicate with said transmitting circuits, the said transmitting circuits being

adjusted to transmit currents of frequencies which are different from and alternating with the frequencies to which said receiving circuits are adjusted.

15. In a multiplex signaling system, a plurality of signal channels employing different frequencies divided into individual pairs each of which constitutes a two-way conversational unit, the two channels of each unit having adjacent frequencies and the frequencies of all the channels being so chosen that those used for transmission in one direction alternate with those used for transmission in the opposite direction.

16. A multiplex transmission system comprising two intercommunicating stations, a plurality of means at each of said stations for transmitting to the other station a plurality of alternating currents representing a corresponding plurality of messages, the frequencies of the currents transmitted by one station being different from those transmitted by the other station and individually alternating therewith.

17. A multiplex carrier current telephone system comprising two intercommunicating stations, a plurality of means at each of said stations for transmitting to the other station a plurality of voice modulated carrier currents, the carrier frequencies of the currents transmitted by one station being different from those transmitted by the other station and individually alternating therewith.

18. A multiplex signaling system comprising in combination a plurality of communicating selective transmitting circuits and a plurality of selective receiving circuits, one of said transmission circuits being used with one of said receiving circuits to constitute the terminal apparatus for each two-way unit of the system, the said transmitting circuits being adjusted to transmit currents of frequencies which are different from and individually alternate with the frequencies to which said receiving circuits are adjusted.

19. In a multiplex signaling system, a plurality of signaling channels employing different frequencies divided into individual pairs, each of which constitutes a two-way unit, the two channels of each unit having adjacent frequencies and the frequencies of all the channels being so chosen that those used for transmission in one direction individually alternate with those used for transmission in the opposite direction.

20. A multiplex transmission system including a conductor for carrying waves corresponding to a plurality of two-way channels, conjugately related input and output circuits corresponding to each channel at a terminal of said conductor, the frequencies transmitted in one direction alternating with those transmitted in the other.

21. A multiplex transmission system employing a plurality of waves of different frequencies for transmitting in each direction, the frequencies transmitted in one direction alternating with those transmitted in the other direction, the spacing between the frequencies being increased as the higher

portion of the employed part of the frequency range is approached.

In witness whereof, I hereunto subscribe my name this 24th day of March, A. D., 1920.

RAYMOND A. HEISING.
